COMBINATION WASHING MACHINE AND
SINK

Rudolph O. Wassamer, Brooklyn, N. Y.

Application March 12, 1940, Serial No. 323,507

9 Claims. (CL 68—4)

This invention relates to new and useful improvements in a combination clothes washing machine and wash tub or wash tub and sink combination.

More specifically, the invention proposes the construction of a washing machine adapted to be mounted on the bottom wall of a wash tub or upon the bottom wall of the wash tub of a combination wash tub and sink.

Still further it is proposed to characterize the washing machine by a motor located beneath said bottom wall and having a stem extending into said wash tub and upon which a wash agitating member is adapted to be releasably mounted in a manner to permit the same to be used for washing clothes when desired.

Still further it is proposed to so characterize the connection between the drive shaft of the motor and wash agitating member so as to permit water to pass upward through the agitating member and dispense therefrom during the agitating process in a manner to increase the washing efficiency of the agitating member.

Still further it is proposed to have the top end of the drive shaft flush with the top face of the bottom wall and to provide the drive shaft with a disc slidably mounted thereon and urged into a normal position in which its top face will be flush with the top face of the bottom wall and the top end of said drive shaft in a manner to provide a flush top face in said wash tub when the agitating member is removed therefrom.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a combination wash tub and sink having a washing machine according to this invention applied thereto.

Fig. 2 is an enlarged vertical sectional view of a portion of Fig. 1.

Fig. 3 is a view similar to a portion of Fig. 2 but illustrating the position of the parts with the wash agitator removed.

Fig. 4 is an elevational view of the top end of the drive shaft.

Fig. 5 is a sectional view taken on the line 5—5 of Fig. 4.

Fig. 6 is a bottom elevational view of the agitating member.

Fig. 7 is a view looking in the direction of the line 7—7 of Fig. 3.

5 The combination washing machine, according to this invention, is adapted to be used on a stationary wash tub or a stationary combination wash tub and sink. In the drawing the washing machine is shown applied to a wash tub and sink 10 which is hung upon a convenient wall 11. This combination comprises a wash tub side 10^a and a sink side 10^b. A back 10^c extends upwards from both the wash tub side 10^a and the sink side 10^b and provides a means for conveniently hanging the combination wash tub and sink. A double faucet 12 having a hot water tap 12^a and a cold water tap 12^b is also provided for the combination wash tub and sink. This faucet 12 has a single outlet 12^c which is pivotally mounted and which is adapted to be turned to direct the water either into the wash tub 10^a or the sink 10^b.

10 The washing machine is characterized by a drive mechanism having a vertically extending shaft 13 extending through the bottom wall of the wash tub 10^a and having its top end flush with the top face of the bottom wall of the wash tub as shown in Fig. 3. This vertical drive shaft 13 extends from a box 14 mounted upon the bottom of the wash tub 10^a by means of several straps 15. This box 14 houses a combination motor, gear reduction unit, and pump. The bottom wall of the wash tub 10 is provided with an enlarged opening 10^{aa} into which the drive shaft 13 extends.

15 A disc 16 is slidably mounted upon the top end of the drive shaft and is keyed thereto to rotate therewith. The disc 16 is provided with an extension 16^a which engages a complementary vertical groove formed in the top end of the drive shaft 13. A ring 17 is welded in position adjacent the open end of the opening 10^{aa} and is adapted to cooperate with the top face of the disc 16 for preventing the complete disengagement of the disc from the opening 10^{aa}. When the disc 16 is in a raised position it has its top face flush with the top face of the bottom wall of the tub 10^a and flush with the top end of the drive shaft 13 for providing a smooth surface on the bottom wall of the tub 10^a, as shown in Fig. 3.

20 A resilient means is provided for holding the disc in its normal raised position. This means comprises an expansion spring 18 coaxially mounted upon the shaft 13 and which operates

between the bottom wall of the opening 10^a and the bottom face of the disc 16.

A wash agitating member 19 is adapted to be mounted upon the top end of the drive shaft 13. This wash agitating member comprises a vertical stem 19^a provided at its top end with a plurality of outwardly extending arms 19^b upon the free end of each of which there is mounted a hollow cup-shaped member 20. The bottom end of the vertical stem 19^a is provided with a socket portion 19^c which is adapted to engage over the top end of the drive shaft 13. The top end of the drive shaft 13 on diametrically opposite sides is provided with bayonet slots 21. Each bayonet slot comprises a vertical portion 21^a extending downwards from the top edge of the drive shaft 13 and continuing into a horizontal portion 21^b.

Each horizontal portion 21^b continues into an upwardly extending portion 21^c extending parallel to the section 21^a and partially towards the top end of the drive shaft 13. The socket end of the wash agitating member 19 is provided with a pair of inwardly extending pins 22 which are adapted to cooperate with the bayonet slots 21 for holding the wash agitating member in position. The socket 19^c is further provided with a rubber member 23 which is adapted to encircle the top end of the drive shaft 13 and seal the adjacent faces thereof.

For engaging the socket member 19^c of the wash agitating member 19 upon the top end of the drive shaft 13 it is merely necessary to align the socket 19^c with the top end of the shaft 13 and the pins 22 with the vertical portion 21^a of the bayonet slots 21. The agitating member 19 is then pressed downwards to urge the disc 16 downwards against the holding action of the spring 18 to cause the pins 22 to move downwards to an aligned position with the horizontal end portions 21^b of the bayonet slots 21. The agitating member 19 is then turned relative to the drive shaft 13 to cause the pins 22 to move along the horizontal portion 21^b of the bayonet slots to an aligned position with the vertical portions 21^c of the bayonet slots 21. The agitating member is then released and the action of the spring 18 will urge the disc 16 and the agitating member 19 upwards relative to the drive shaft 13 to cause the pins 22 to be engaged against the top wall of the vertical portions 21^c of the bayonet slots 21. This is the locked position of the agitating member 19 with relation to the drive shaft 13, and as the drive shaft turns the agitating member will turn therewith.

A means is provided for locking the shaft 13 against rotating when the pins 22 are in an aligned position with the horizontal portions 21^b of the bayonet slots 21 for permitting the agitating member to be turned relative thereto. This means comprises teeth 24 formed on the outer periphery of the disc 16 and which are adapted to engage with complementary teeth 25 formed on a ring 26 mounted upon the vertical walls of the opening 10^a. When the agitating member has pressed the disc 16 downwards to a position in which the pins 22 will be aligned with the horizontal portions 21^b the teeth 24 and 25 will be engaged, and since the disc 16 is keyed to the shaft 13 it will be impossible for the shaft 13 to turn and relative movement between the agitating member 19 and the shaft 13 will be possible to permit the pins to be aligned with either vertical portion 21^a or 21^c of the bayonet slots 21.

A novel means is also provided for circulating the water through the wash tub 10^a. This

means comprises a pipe 27 connecting with the interior of the wash tub 10^a and with the pump mounted within the container 14. A second pipe 28 extends from the pump and connects with the opening 10^a as shown in Figs. 2 and 3. The drive shaft 13 is provided with open side walls 13^a which connect with a vertically extending opening 13^b extending through the center thereof. This vertically extending opening 13^b connects with a vertically extending opening 19^d formed in the stem 19^a of the agitating member 19. The top end of the vertically extending opening 19^d continues in a plurality of branches 19^e, one for each of the arms 19^b of the agitating member 19. The branches 19^e connect with the interior of each of the hollow cup-shaped members 20. The bottom face of each cup-shaped member is provided with a plurality of openings 20^a through which the water is adapted to again discharge.

A drainage system is also provided for draining the water from the wash tub, the sink and the pump mounted within the container 14. This means comprises a drain pipe 29 extending from the sink 10^b and which is provided with a conventional S-shaped trap 29^a. An auxiliary drain pipe 30 extends from the interior of the wash tub 10^a and is provided with a valve 31 which is adapted to be closed to prevent the loss of water therethrough. A second auxiliary drain pipe 32 extends from the pipe 28 for draining the water from the pump and is provided with a valve 33 for preventing the loss of water therethrough. Each of the branch pipes 30 and 32 connect with the drain 29 as shown in Fig. 2.

The operation of this invention is as follows:

The agitating member is mounted on the top end of the drive shaft as hereinbefore described. The wash tub 10^a is then filled with water by opening the taps 12^a and 12^b of the faucet 12. The clothes to be washed are then placed within the wash tub and the combination motor, gear reduction unit and pump is brought into operation. The operation of the motor will cause the drive shaft 13 to rotate and also rotate the agitating member 19. The operation of the motor will cause the pump to also operate. As the pump operates it will draw water from the wash tub 10^a through the pipe 27. This water will then be discharged back into the tub 10^a through the pipe 28 and the aligned openings 13^b and 19^d to discharge through the openings 20^a formed in the hollow cup-shaped member 20. This water will be forced from the cup-shaped members 20 under pressure to add to the operation of the agitating member in washing the clothes.

When desired it is possible to use the wash tub 10^a without the agitating member 19 by merely removing the same from the free end of the drive shaft 13. In this removed position the disc 16 will be urged upwards into a flush position with the top face of the bottom wall and the top end of the drive shaft 13 providing a smooth bottom face within the tub 10^a.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a washing machine of the class described,

a tub having a bottom wall, a drive mechanism having a vertical shaft extending through said bottom wall and having its top end flush with the top face of said bottom wall, and its top portion provided with bayonet slots, a disc keyed on said shaft and slidably mounted thereon and normally having its top face flush with the top face of said bottom wall, resilient means for holding said disc in its normal position, means for holding said disc from turning in a lowered position, and a wash agitating member for location in said tub and having a bottom socket portion with pins engageable with said bayonet slots.

2. In a washing machine of the class described, a tub having a bottom wall, a drive mechanism having a vertical shaft extending through said bottom wall and having its top end flush with the top face of said bottom wall, and its top portion provided with bayonet slots, a disc keyed on said shaft and slidably mounted thereon and normally having its top face flush with the top face of said bottom wall, resilient means for holding said disc in its normal position, means for holding said disc from turning in a lowered position, and a wash agitating member for location in said tub and having a bottom socket portion with pins engageable with said bayonet slots, said resilient means comprising a spring operating between the bottom face of said disc and a portion of said tub.

3. In a washing machine of the class described, a tub having a bottom wall, a drive mechanism having a vertical shaft extending through said bottom wall and having its top end flush with the top face of said bottom wall, and its top portion provided with bayonet slots, a disc keyed on said shaft and slidably mounted thereon and normally having its top face flush with the top face of said bottom wall, resilient means for holding said disc in its normal position, means for holding said disc from turning in a lowered position, and a wash agitating member for location in said tub and having a bottom socket portion with pins engageable with said bayonet slots, said means for holding said disc comprising teeth formed on the outer periphery of said disc, a ring mounted beneath said disc, and teeth formed on said ring and cooperative with said teeth in lowered position of said disc for holding said disc against rotating.

4. In a washing machine of the class described, a tub having a bottom wall, a drive mechanism having a vertical shaft extending through said bottom wall and having its top end flush with the top face of said bottom wall, and its top portion provided with bayonet slots, a disc keyed on said shaft and slidably mounted thereon and normally having its top face flush with the top face of said bottom wall, resilient means for holding said disc in its normal position, means for holding said disc from turning in a lowered position, and a wash agitating member for location in said tub and having a bottom socket portion with pins engageable with said bayonet slots, said disc being provided with a projection engaging a groove formed in said drive shaft forming the means for keying said disc to said shaft.

5. In a washing machine of the class described, a tub having a bottom wall, a drive mechanism located beneath said bottom wall, a vertical shaft extending from said drive mechanism through said bottom wall and having its top end flush with the top face of said bottom wall, and a wash agitating member located within said tub and re-

movably mounted on the top end of said shaft, whereby when desired said wash agitating member may be removed from said tub forming a tub having an interior clear of any obstruction to be used for other purposes, said removable mounting of said wash agitating member, comprising a socket formed on the bottom end of said wash agitating member and engageable over the top end of said vertical shaft, inwardly extending pins mounted within said socket and engageable with complementary bayonet slots formed on the top end of said shaft, each bayonet slot, comprising a vertical portion extending downwards from the top end of said vertical shaft, a transverse portion extending from the bottom of said vertical portion, a dead-end vertical portion continuing from the free end of said transverse portion and extending upwards to a position adjacent the top end of said shaft, and means for urging said wash agitating member into a position in which said pins will abut the two ends of the dead-end vertical portions of said bayonet slots.

6. In a washing machine of the class described, a tub having a bottom wall, a drive mechanism located beneath said bottom wall, a vertical shaft extending from said drive mechanism through said bottom wall and having its top end flush with the top face of said bottom wall, and a wash agitating member located within said tub and removably mounted on the top end of said shaft, whereby when desired said wash agitating member may be removed from said tub forming a tub having an interior clear of any obstruction to be used for other purposes, said removable mounting of said wash agitating member, comprising a socket formed on the bottom end of said wash agitating member and engageable over the top end of said vertical shaft, inwardly extending pins mounted within said socket and engageable with complementary bayonet slots formed on the top end of said shaft, each bayonet slot, comprising a vertical portion extending downwards from the top end of said vertical shaft, a transverse portion extending from the bottom of said vertical portion, a dead-end vertical portion continuing from the free end of said transverse portion and extending upwards to a position adjacent the top end of said shaft, and means for urging said wash agitating member into a position in which said pins will abut the two ends of the dead-end vertical portions of said bayonet slots, comprising a disc vertically slidably keyed to said shaft and engageable against the bottom end of said wash agitating member, said disc being located within a recess formed in the bottom wall of said tub, and means within said recess for urging said disc upwards to in turn urge said wash agitating member upwards to cause said pins to retain their operative position within the dead-end vertical portion of said bayonet slots.

7. In a washing machine of the class described, a tub having a bottom wall, a drive mechanism located beneath said bottom wall, a vertical shaft extending from said drive mechanism through said bottom wall and having its top end flush with the top face of said bottom wall, and a wash agitating member located within said tub and removably mounted on the top end of said shaft, whereby when desired said wash agitating member may be removed from said tub forming a tub having an interior clear of any obstruction to be used for other purposes, said removable

mounting of said wash agitating member, comprising a socket formed on the bottom end of said wash agitating member and engageable over the top end of said vertical shaft, inwardly extending pins mounted within said socket and engageable with complementary bayonet slots formed on the top end of said shaft, each bayonet slot, comprising a vertical portion extending downwards from the top end of said vertical shaft, a transverse portion extending from the bottom of said vertical portion, a dead-end vertical portion continuing from the free end of said transverse portion and extending upwards to a position adjacent the top end of said shaft, and means for urging said wash agitating member into a position in which said pins will abut the two ends of the dead-end vertical portions of said bayonet slots, comprising a disc vertically slidably keyed to said shaft and engageable against the bottom end of said wash agitating member, said disc being located within a recess formed in the bottom wall of said tub, and means within said recess for urging said disc upwards to in turn urge said wash agitating member upwards to cause said pins to retain their operative position within the dead-end vertical portion of said bayonet slots, comprising an expansion spring coaxially mounted upon said shaft and operating between the bottom face of said disc and the bottom wall of said recess.

8. In a washing machine of the class described, a tub having a bottom wall, a drive mechanism located beneath said bottom wall, a vertical shaft extending from said drive mechanism through said bottom wall and having its top end flush with the top face of said bottom wall, and a wash agitating member located within said tub and removably mounted on the top end of said shaft, whereby when desired said wash agitating member may be removed from said tub forming a tub having an interior clear of any obstruction to be used for other purposes, said removable mounting of said wash agitating member, comprising a socket formed on the bottom end of said wash

agitating member and engageable over the top end of said vertical shaft, inwardly extending pins mounted within said socket and engageable with complementary bayonet slots formed on the top end of said shaft, said bottom wall being formed with a recess having a diameter greater than said socket so that said socket may be engaged upon the top end of said shaft, and means for closing the space between the peripheral edge of said shaft and the material of said bottom wall around said recess when said wash agitating member is removed from said shaft.

9. In a washing machine of the class described, a tub having a bottom wall, a drive mechanism located beneath said bottom wall, a vertical shaft extending from said drive mechanism through said bottom wall and having its top end flush with the top face of said bottom wall, and a wash agitating member located within said tub and removably mounted on the top end of said shaft, whereby when desired said wash agitating member may be removed from said tub forming a tub having an interior clear of any obstruction to be used for other purposes, said removable mounting of said wash agitating member, comprising a socket formed on the bottom end of said wash agitating member and engageable over the top end of said vertical shaft, inwardly extending pins mounted within said socket and engageable with complementary bayonet slots formed on the top end of said shaft, said bottom wall being formed with a recess having a diameter greater than said socket so that said socket may be engaged upon the top end of said shaft, and means for closing the space between the peripheral edge of said shaft and the material of said bottom wall around said recess when said wash agitating member is removed from said shaft.

RUDOLPH O. WASSMER.
